(57) **CLAIM**

The ornamental design for a battery, as shown and described.

DESCRIPTION

FIG. 1 is a perspective view of the battery of the present invention;

FIG. 2 is a front view of the battery of the present invention; FIG. 3 is a rear view of the battery of the present invention; FIG. 4 is a left side view of the battery of the present invention;

FIG. 5 is a right side view of the battery of the present invention;

FIG. 6 is a top plan view of the battery of the present invention; and,

FIG. 7 is a bottom view of the battery of the present invention.

The broken lines throughout the drawing figures are included for the purpose of illustrating portions of the battery that form no part of the claimed design.
